CLAIM

The ornamental design for an electrical vehicle charging pedestal as shown and described.

DESCRIPTION

FIG. 1 is a front side perspective view of an electric vehicle charging pedestal according to a first embodiment.

FIG. 2 is a left side elevational view of the electric vehicle charging pedestal of FIG. 1, the right side being a mirror image.

FIG. 3 is a rear elevational view of the electric vehicle charging pedestal of FIG. 1.

FIG. 4 is a top plan view of the electric vehicle charging pedestal of FIG. 1.

FIG. 5 is a bottom plan view of the electric vehicle charging pedestal of FIG. 1.

FIG. 6 is a front side perspective view of the electric vehicle charging pedestal of FIG. 1 with an access door in an open position.

FIG. 7 is a front side perspective view of the electric vehicle charging pedestal of FIG. 1 showing an operating environment which includes electric vehicle charging equipment in a first arrangement.

FIG. 8 is a front side perspective view of the electric vehicle charging pedestal of FIG. 1 showing an operating environment which includes electric vehicle charging equipment in a second arrangement.

FIG. 9 is a front side perspective view of the electric vehicle charging pedestal of FIG. 1 showing an operating environment which includes electric vehicle charging equipment in a third arrangement.

FIG. 10 is a front side perspective view of the electric vehicle charging pedestal of FIG. 1 showing an operating

(Continued)

environment which includes electric vehicle charging equipment in a fourth arrangement.

FIG. 11 is a front side perspective view of an electric vehicle charging pedestal according to a second embodiment.

FIG. 12 is a left side elevational view of the electric vehicle charging pedestal of FIG. 11, the right side being a mirror image.

FIG. 13 is a rear elevational view of the electric vehicle charging pedestal of FIG. 11.

FIG. 14 is a top plan view of the electric vehicle charging pedestal of FIG. 11; and,

FIG. 15 is a bottom plan view of the electric vehicle charging pedestal of FIG. 11.

The broken lines depict portions of the electrical vehicle charging pedestal that form no part of the claimed design.
